CLAIM

The ornamental design for a bumper/grille guard for vehicles, as shown and described.

DESCRIPTION

FIG. 1 is a top, front, and right side perspective view of a bumper/grille guard for vehicles showing my new design; FIG. 2 is a front elevation view thereof;

FIG. 3 is a left side elevation view thereof;

FIG. 4 is a right side elevation view thereof;

FIG. 5 is a top plan view thereof;

FIG. 6 is a bottom plan view thereof; and

FIG. 7 is a rear elevation view thereof.

*FIG. 8 is a top, front, and right side perspective view of a bumper/grille guard for vehicles showing my new design in accordance to an alternate embodiment;**FIG. 9 is a front elevation view thereof;**FIG. 10 is a left elevation view thereof;**FIG. 11 is a right side elevation view thereof;**FIG. 12 is a top plan view thereof;**FIG. 13 is a bottom plan view thereof; and,**FIG. 14 is a rear elevation view thereof.*

The broken lines shown in the figures illustrate portions of the bumper/grille guard for vehicles that form no part of the claimed design.

1 Claim, 10 Drawing Sheets**Matter enclosed in heavy brackets [ ] appears in the original patent but forms no part of this reissue; matter printed in italics indicates the additions made by reissue.**(56)
